US00D504121S

(12) **United States Design Patent** (10) Patent No.: **US D504,121 S**
Robertson, Jr. et al. (45) Date of Patent: **** Apr. 19, 2005**

(54) **COMMUNICATION DEVICE**

(75) Inventors: **William H. Robertson, Jr.**, Ft. Lauderdale, FL (US); **Franco Lodato**, Weston, FL (US); **John Kelley**, Sunnyvale, CA (US)

(73) Assignee: **Motorola, Inc.**, Schaumburg, IL (US)

(**) Term: **14 Years**

(21) Appl. No.: **29/206,131**

(22) Filed: **May 26, 2004**

(51) LOC (7) Cl. **14-03**

(52) U.S. Cl. **D14/138**

(57) **CLAIM**

The ornamental design for a communication device, as shown and described.

DESCRIPTION

FIG. 1 is an isometric view of a communication device showing our new design.

FIG. 2 is a front orthographic view thereof.

FIG. 3 is a rear orthographic view thereof.

FIG. 4 is a left side orthographic view thereof.

FIG. 5 is a right side orthographic view thereof.

FIG. 6 is a top orthographic view thereof.

FIG. 7 is a bottom orthographic view thereof.

FIG. 8 is an isometric view of a second embodiment of a communication device showing our new design.

FIG. 9 is a front orthographic view thereof.

FIG. 10 is a rear orthographic view thereof.

FIG. 11 is a left side orthographic view thereof.

FIG. 12 is a right side orthographic view thereof.

FIG. 13 is a top orthographic view thereof; and,

FIG. 14 is a bottom orthographic view thereof.

The broken lines shown in FIGS. 1-7 are included for the purpose of illustrating environmental elements only and form no part of the claimed design.
